US00D935013S

(12) **United States Design Patent** (10) **Patent No.:** **US D935,013 S**
Greenberg et al. (45) **Date of Patent:** **** Nov. 2, 2021**

(54) **CATHETER**

(71) Applicant: **EMMY MEDICAL, LLC**, Holliston, MA (US)

(72) Inventors: **James Adam Greenberg**, Weston, MA (US); **Neeraj Kohli**, Natick, MA (US); **Ronald David Adams**, Holliston, MA (US)

(73) Assignee: **Emmy Medical, LLC**, Holliston, MA (US)

(**) Term: **15 Years**

(21) Appl. No.: **29/767,531**

(22) Filed: **Jan. 22, 2021**

Related U.S. Application Data

(63) Continuation of application No. 29/660,163, filed on Aug. 17, 2018, now Pat. No. Des. 908,865.

(57) **CLAIM**

The ornamental design for a catheter, as shown and described herein.

DESCRIPTION

FIG. 1 is a perspective view of a catheter embodying the new design.

FIG. 2 is a front view thereof.

FIG. 3 is a rear view thereof.

FIG. 4 is a first side view thereof.

FIG. 5 is a second side view thereof.

FIG. 6 is a top view thereof; and,

FIG. 7 is a bottom view thereof.

All features in broken lines are for the purpose of illustrating environmental structure and form no part of the claimed subject matter.

1 Claim, 6 Drawing Sheets
